UNITED STATES PATENT OFFICE.

EDWARD STANLEY GARY, JR., OF BALTIMORE, MARYLAND.

BUNCH-BUILDER FOR WINDING-MACHINES.

1,378,171.

Specification of Letters Patent. Patented May 17, 1921.

Application filed October 18, 1920. Serial No. 417,689.

To all whom it may concern:

Be it known that I, EDWARD STANLEY GARY, Jr., a citizen of the United States, residing at Baltimore city, State of Maryland, 5 have invented certain new and useful Improvements in Bunch-Builders for Winding-Machines, of which the following is a specification.

This invention relates to improvements 10 in machines for winding silk, linen or other threads, or yarn, on bobbins, and more particularly to the mechanism known as bunch-builders. These devices are usually composed of moving parts subject to changed 15 adjustment and looseness from wear, and also requiring lubrication, which often results in the yarn getting soiled with oil, causing oil streaks in the finished cloth, damaging its value and preventing the 20 proper taking of dyes. The invention has for its object to remedy these faults or defects in the mechanism as heretofore constructed, and to provide a structure which is very simple and without moving parts, and 25 withal, highly efficient in operation.

The object stated is attained by means of a novel device to be hereinafter described and claimed, and in order that the same may be better understood, reference is had to the 30 accompanying drawing forming a part of this specification.

In the drawing—

Figure 1 is a plan view showing the application of the invention; Fig. 2 is a cross-section on the line 2—2 of Fig. 1, and Fig. 3 is a perspective view of the device detached.

Referring specifically to the drawing, 5 denotes the bobbin on which the thread or yarn is to be wound. One end of the bobbin 5 extends into the usual former cone 6 having a top slot 7 through which the thread passes to the bobbin. These parts are constructed and arranged in the usual manner, and hence a detailed description 40 thereof is not necessary.

Above the thread slot 7 of the cone 6 is positioned the thread guide of the traversing mechanism, and as this mechanism forms no part of the present invention, it 50 has not been illustrated, its operation being well understood by those skilled in the art. The thread guide is a wire rod 8 having one end doubled and bent to form an angular thread slot, one portion 9 of the slot 55 extending parallel to the axis of the bobbin

5, and the other portion 10 extending transversely of the bobbin axis.

On top of the cone 6, at one side of the slot 7, is rigidly mounted a thread restraining device in the form of a hook 11 which 60 overhangs the slot 7 and has a longitudinally slotted shank 12 to take a cap screw 13 whereby it is fastened to the cone, the slot 65 permitting adjustment of the hook relative to the slot.

In order that a bunch of thread may be formed on the bobbin 5 before the main body of the winding is laid thereon, it is necessary to hold the thread out of the traverse until a bunch of the proper size is wound, 70 after which the thread is allowed to take up its regular winding. This operation is automatically effected by the hook 11 in conjunction with the thread guide of the traverse mechanism. At the commencement 75 of the bunch wind, the thread lies in the slot 9 of the thread guide, and thence passes down through the slot 7 to the bobbin, it being engaged at this slot by the bill of the hook 11 and held thereby in the slot 9. It 80 will be evident that the thread is now guided to the bobbin without any traverse motion, this being due to the fact that the movement of the thread guide has no effect on the thread in the slot 9, as the latter is parallel 85 to the bobbin and to the direction in which the traverse mechanism moves the thread, it being understood that the thread guide is carried back and forth along the bobbin 5. However, this movement of the thread guide 90 has no effect on the thread when the latter is passing through the slot 9. As the bunch builds up on the bobbin and its diameter or girth increases, the course of the thread as it runs to the bobbin also changes as shown by 95 dotted lines in Fig. 2, the thread gradually moving in a direction transversely of the slot 9 and in the direction of the extremity of the hook 11, until it slips off the latter, and as it is now no longer restrained or 100 held in the slot 9, it slips into the slot 10 when the latter comes opposite. As soon as the thread enters the slot 10, the traverse motion starts as this slot runs transverse to the bobbin and the path in which the thread 105 guide reciprocates, so that the thread is now carried directly to the bobbin and moved back and forth along the latter by the traverse mechanism. The hook 11 is readily adjustable so that it may be properly posi-

tioned relative to the thread slot 7 and the thread guide of the traverse according to the size of the bunch to be formed.

The device is very simple in construction, and highly efficient in operation, and it can be readily attached to the machine without changes or modifications in the structure thereof.

I claim:

1. In a winding machine, the combination with a bobbin, and the thread guide of a traverse mechanism, said guide having a thread-engaging portion and a slot leading thereto, said slot extending parallel to the direction of the strokes of the thread guide; of a restraining device engageable by the thread in its passage from the thread guide to the bobbin, said device being positioned to hold the thread in the aforesaid slot to permit a building up of a bunch on the bobbin, said bunch by its increasing diameter operating to automatically disengage the thread from the restraining device and permit passage of the thread to the thread-engaging portion of the thread guide.

2. In a winding machine, the combination with a bobbin, and the thread guide of a traverse mechanism, said guide having a thread passage running transversely of the direction in which the guide travels and an-

other passage leading thereto and running parallel to the direction of travel of the guide; of a restraining device engageable by the thread in its passage from the thread guide to the bobbin, said device being positioned to hold the thread in the second-mentioned passage of the thread guide to permit a building up of a bunch on the bobbin, said bunch by its increasing diameter operating to automatically disengage the thread from the restraining device and permit movement of the thread to the first-mentioned passage of the thread guide.

3. In a winding machine, the combination with a bobbin, and the thread guide of a traverse mechanism, said guide having a thread-engaging portion and a slot leading thereto, said slot extending parallel to the direction of travel of the guide; of a hook engageable by the thread in its passage from the thread guide to the bobbin, said hook being positioned to hold the thread in the aforesaid slot to permit a building up of a bunch on the bobbin, said bunch by its increasing diameter operating to automatically disengage the thread from the hook and permit passage of the thread to the thread-engaging portion of the thread guide.

In testimony whereof I affix my signature.

EDWARD STANLEY GARY, JR.
